Term of patent 3½ years

(Cl. D33—19)

FIG. 2

FIG. 3

Fig. 1 is a front perspective view of a chest-on-chest showing our new design.

Fig. 2 is an enlarged detail of a section taken on the line 2-2 of Fig. 1 showing the door molding.

Fig. 3 is a sectional view taken on the line 3-3 of Fig. 1.

The characterizing feature of the invention resides in the upper cabinet portion, an essential feature of which includes the concave curve of the bordering frame in its relation to the re-entrant central panel as indicated in Fig. 3.

We claim:

The ornamental design for a chest-on-chest, as shown and described.
